UNITED STATES PATENT OFFICE.

CHARLES ERNEST JONES, OF CHICAGO, ILLINOIS.

DESIGN FOR A HUSK FOR LIGHTING-FIXTURES.

51,382.

Specification for Design.

Patented Oct. 16, 1917.

Application filed March 6, 1917. Serial No. 152,936. Term of patent 3½ years.

To all whom it may concern:

Be it known that I, CHARLES ERNEST JONES, a citizen of the United States, residing at Chicago, in the county of Cook and State of Illinois, have invented a new, original, and ornamental Design for a Husk for Lighting-Fixtures, of which the following is a specification, reference being had to the accompanying drawing, wherein—

Fig. 1 is a plan view, and

Fig. 2 is a side elevation of a husk for lighting fixtures, showing my new design.

I claim as my invention:

The ornamental design for a husk for lighting fixtures, as shown.

CHARLES ERNEST JONES.
